UNITED STATES PATENT OFFICE.

GEORGE REED NAPIER, OF MACON, GEORGIA.

CENTRIFUGAL CHOPPER.

1,188,475.

Specification of Letters Patent. Patented June 27, 1916.

Application filed October 25, 1915. Serial No. 57,725.

To all whom it may concern:

Be it known that I, GEORGE R. NAPIER, a citizen of the United States, residing at Ma-
5 con, in the county of Bibb and State of
Georgia, have invented certain new and use-
ful Improvements in Centrifugal Choppers;
and I do declare the following to be a full,
10 clear, and exact description of the invention,
such as will enable others skilled in the art to
which it appertains to make and use the
same.

My invention has relation to that class of
machines designed for chopping meat, such
as that used for sausage, and the object of
15 the invention is to provide a machine of this
class relying upon centrifugal force for feed-
ing the meat to the cutting knives. In ac-
complishing this end, I provide certain novel
20 features of construction and unique combi-
nations of parts to be hereinafter fully de-
scribed and claimed.

In describing the invention, I shall refer
by reference numerals to the accompanying
drawings which constitute a part of this ap-
25 plication and in which,

Figure 1 is a side elevation with parts
broken away, showing one type of the inven-
tion; Fig. 2 is a vertical section as viewed on
30 the plane designated by the line 2—2 of Fig.
1; and Fig. 3 is a vertical section of a differ-
ent style of machine.

In Figs. 1 and 2, the numeral 1 designates
an appropriate base with which spaced
standards 2 and 3 are preferably formed in-
35 tegrally. The standard 2 carries a bearing
4 at its upper end in which a horizontal shaft
5 is rotatably mounted. Keyed to the inner
end of the shaft 5 is the hub 6 of a circular
40 wall 7 which constitutes one end of a rotary
drum 8, the cylindrical wall 9 of such drum
being shown as formed integrally with the
wall 7. The other end wall 10 of the drum
8 is secured in position by screws or the like
45 and is provided with a circular inlet open-
ing 12. For a reason to become obvious, the
wall 9 is lined with a series of wooden blocks
13 or with blocks or the like of other appro-
priate material.

As shown most clearly in Fig. 2, the drum
50 8 is interposed between the standards 2 and
3, the latter being of less height than the
former and having at its upper end a bearing
opening 14 whose axis is disposed parallel to
the shaft 5. Mounted for rotation in the
55 opening 14, but normally held against such
movement therein by a lock nut or an equiva-

lent device 15, is an eccentric 16 formed on
one end of the shaft 17 which projects eccen-
trically through the opening 12 into the
drum 8. Rotatable and slidable on the shaft
17 is a hub 18 carrying a plurality of axially
aligned cutting disks 19 which travel on the
lining of the wall 9.

One end of the hub 18 is grooved circum-
ferentially for the reception of a fork 20 on
the inner end of a horizontal rod 21 which
is slidable in an opening formed in the
standard 3 above the bearing opening 14.
By the provision of the rod 21 and its fork
20, it is obvious that the hub 18 and its disks
19 may be so shifted on the shaft 17 as to
cause said disks to contact with different
parts of the lining blocks 13, thus preventing
such lining blocks from becoming worn only
on certain paths. As the disks 19 are de-
creased in size by continual use and grinding,
the eccentric 16 may be adjusted to al-
ways cause such disks to contact with the
blocks 13, as will be obvious from an in-
spection of the drawings.

In operating the machine, the meat or the
like to be chopped is deposited into the drum
8 through the opening 12 therein and such
drum is rotated at a high speed either by
the provision of a belt 22 shown in Fig. 1 or
35 the crank 23 depicted in Fig. 2. The result
is that the meat is thrown outwardly against
the lining blocks 13 by centrifugal force and
is fed beneath the cutting disks 19.

Fig. 3 discloses a drum 8^a similar in con-
struction to that above described but mount-
ed on an upright axis 5^a and rotated through
the instrumentality of a gear and pinion 24
and 25 respectively, the latter being driven
from the shaft 26 equipped with loose and
tight pulleys 27 and 28 respectively, or with
other preferred means. In this type of the
invention, cutting disks 19^a similar to those
designated at 19 are provided, with their
axes disposed parallel to the axis 5^a, while at
90 a point spaced from the disks 19^a a rotary
cutter 29 is employed having a plurality of
cutting blades 30 for contact with the lining
of the drum, said blades being positioned at
95 an angle to the disks 19^a, whereby to cut the
material in the drum in intersecting planes.
The shafts 17^a and 29^a of the cutters 19^a and
29 are preferably provided with eccentrics
16^a at their upper ends similar to the eccen-
tric 16 previously described. These eccen-
trics are mounted in bearings carried by the
horizontal frame bar 31 above the drum 8^a.

and having its ends secured to arms or the like 32 rising from a leg supported base plate 33 disposed beneath said drum. As clearly shown, the frame bar 31 and plate 33 serve 5 as anchoring means for the opposite ends of the shaft 5^a upon which the drum rotates.

The operation of the form just described is identical with that previously defined, and further description is therefore deemed unnecessary. It will be obvious that both 10 types of the machine will be efficient and durable and will fulfil long felt needs in the art to which they relate.

In the drawings certain specific details of 15 construction have been shown for illustrative purposes, and in the foregoing such details have been described, but it is obvious that numerous changes may be made within the scope of the invention as claimed, without 20 sacrificing any of the advantages thereof.

I claim:

1. A centrifugal chopper comprising a rotary drum having adjacent the inner side of its curved wall a number of axially alined 25 cutting disks traveling on said wall and having their axes disposed parallel to the axis of the drum, and a rotary cutter spaced from the disks and having a plurality of cutting blades disposed at an angle in respect thereto 30 to and positioned for contact with the aforesaid curved wall of the drum.

2. A centrifugal chopper comprising a rotary drum having in one end a circular inlet opening, a shaft projecting eccentrically into 35 said opening and disposed in parallel relation with the axis of the drum, an elongated hub rotatably mounted on said shaft and carrying a plurality of axially alined cutting disks traveling on the inner curved side 40 of the drum, and means for adjusting the hub longitudinally on the shaft to prevent

excessive mutilation of the drum by constant engagement of the disks with the same portions thereof.

3. A centrifugal chopper comprising a rotary drum having in one end a central inlet opening, a bearing disposed contiguous to said end and having its axis disposed in parallel relation to the axis of the drum, a shaft positioned eccentrically in said drum and having on its outer end an eccentric rotatably mounted in the bearing, whereby rotation of said eccentric will vary the distance between the shaft and the curved wall of the drum, means for locking the eccentric 55 against rotation, and a plurality of axially alined cutting disks mounted on the shaft and traveling on said curved wall of the drum.

4. A centrifugal chopper comprising a rotary drum having in one end a central inlet opening, a bearing disposed contiguous to said end and having its axis disposed in parallel relation to the axis of the drum, a shaft positioned eccentrically in said drum and having on its outer end an eccentric rotatably mounted in the bearing, whereby rotation of said eccentric will vary the distance between the shaft and the curved wall of the drum, means for locking the eccentric 60 against rotation, and a plurality of axially alined cutting disks mounted on the shaft and traveling on said curved wall of the drum, 65 means for adjusting said eccentric longitudinally on the shaft.

In testimony whereof I have hereunto set my hand in presence of two subscribing witnesses.

GEORGE REED NAPIER.
